(57) **CLAIM**

We claim the ornamental design for the one-step work platform, as shown and described.

DESCRIPTION

FIG. 1 is an overhead perspective view of a work platform showing our new design;

FIG. 2 is an end elevational view thereof, the view from the other side being a mirror image of FIG. 2;

FIG. 3 is a side elevational view thereof, the view from the other side being a mirror image of FIG. 3;

FIG. 4 is a top plan view thereof;

FIG. 5 is a bottom plan view thereof; and,

FIG. 6 is an underside perspective view thereof showing our new design in a closed position.
